UNITED STATES PATENT OFFICE.

DAVID KENDALL, OF ALLIANCE, OHIO, ASSIGNOR TO THE ALLIANCE MACHINE COMPANY, OF ALLIANCE, OHIO, A CORPORATION OF OHIO.

SLAB-CHARGER.

1,259,023.

Specification of Letters Patent. Patented Mar. 12, 1918.

Application filed May 12, 1916. Serial No. 97,208.

To all whom it may concern:

Be it known that I, DAVID KENDALL, a citizen of the United States, residing at Alliance, in the county of Stark and State of Ohio, have invented a new and useful Improvement in Slab-Chargers, of which the following is a full, clear, and exact description, reference being had to the accompanying drawings, forming part of this specification, in which

Figure 1 is a side elevation of a portion of one type of charger built in accordance with my invention.

Fig. 2 is a plan view of the gearing for 15 rotating the supporting column of the charger.

Fig. 3 is a sectional view on the line III—III of Fig. 2.

Fig. 4 is a detailed sectional view on the 20 line IV—IV of Fig. 2 on a larger scale.

Fig. 5 is a plan view of one of the friction rings, and

Fig. 6 is a detailed plan view of a portion of the sectional bushing.

This invention relates to an improvement 25 in driving mechanism for rotating the column or support for charging apparatus, cranes and other similar devices and is designed to provide an efficient device of this character which can be readily assembled and in which the parts are so arranged that when the motor for rotating the column is stopped, the momentum of the column will be quickly overcome, so that the rotation of 30 the column will be stopped immediately after the power of the motor has been cut off.

Another object of my invention is to provide a device of this character which is so arranged that if the charging beam or load 40 support should accidentally come in contact with a column or any other obstruction, said support would be stopped and the motor would be permitted to run without causing any serious damage to the mechanism.

Heretofore in charging apparatus of this 45 general type, the motor was directly geared to the rotatable support or column and when the power was shut off, the momentum of the support would frequently carry the 50 arm and the load supported thereby beyond the desired point, the amount of movement depending upon the weight of the load and the momentum at the time the power was cut off.

It is well known to those familiar with the

art that in places where charging cranes of this character are used in connection with furnaces, supporting columns for building and crane structures are frequently so placed that they are liable to be struck by the load supporting arm when charging, and when this happens a wreck occurs.

I overcome these various objections by interposing between the driving gear for the supporting column and the supporting column, a plurality of friction disks which are alternately connected to the column and the gear and are arranged in such a manner that the column and the load being charged thereby act to hold the disks in frictional 60 contact with each other so that the greater the load the greater the friction on said disks.

The precise nature of my invention will be best understood by reference to the accompanying drawings which will now be 75 described, it being premised, however, that various changes may be made in the details of construction and the general arrangement of the parts without departing from the spirit and scope of my invention, as defined in the appended claims.

In the drawings, the reference character 2 designates a crane runway supported by columns 3 and adjacent to a furnace 4 which is to be charged with slabs. Movable mounted on the runway 2 is a crane bridge 5, and 80 6 is a trolley which is arranged to move longitudinally over the bridge or transversely with relation to the building. Mounted on the bridge 5 is a motor 7 which is geared to 85 the driving mechanism of the bridge and which is arranged to move the entire crane longitudinally over the runway 2. 9 is a motor mounted on the trolley and is arranged to move the trolley along the bridge 90 by means of gearing 10 connected to one or more of the supporting wheels for the trolley. Connected to the frame work of the trolley 6 is an annular bearing 11, and rotatably mounted in this bearing is an upwardly 100 extending stem 12, having a column 13 sustained therefrom. 14 is the frame for the charging apparatus which is arranged to be moved vertically within the column by means of a motor 15 and suitable gearing 16 105 which is connected to the cables in the usual manner.

Mounted on this charging apparatus is the operator's stand 17 and a charging arm 18, which is arranged to engage a billet, such 110

as shown at 19 in Fig. 1, and transfer the same into the furnace 4, or a similar furnace adjacent thereto.

The upper portion of the stem 12 is provided with an annular flange 20, and 21 is a two-piece collar having an annular flange which engages the annular flange 20. 22 is a two-piece bushing surrounding the stem 12 below the collar 21 and which is arranged 10 to form a bearing for a gear member 23 having teeth 24 on its periphery. This gear member 23 is provided with an annular recess and seated within this recess are a plurality of friction disks 25 and 26. The 15 friction disks 25 and 26 are placed in alternate relation, the disks 25 being keyed to the gear wheel 24 by means of keys 27, while the disks 26 are keyed to a flanged collar 28 by means of keys 29. This flanged collar 20 surrounds the two-part collar 21 and is held in position on said collar by means of a two-part ring 30 which is seated in an annular recess in the collar 21. The gear member 23 is supported on rollers 31 interposed between 25 it and the top of the bearing 11, there being a certain amount of play between the flanged collar 28 and the gear member so that the entire load supported by the stem 12 is sustained by the gear member 23 through the 30 interpositioned disk members 25 and 26.

Each of the friction rings 25 and 26 as well as the lower face of the flanged collar 28 and the upper face of the gear member 23 are provided with friction disks, such 35 as indicated at 32 in Figs. 3, 4 and 5, of any well known character.

The collar 28 and the gear member are merely provided with recesses for receiving the friction disks, while the friction rings 40 are provided with through openings for the reception of said disks, which disks are arranged to frictionally engage the surfaces of members on opposite sides of the disks. 33 is a pinion meshing with the gear teeth 45 24 on the gear member 23, which pinion is connected to a shaft 34, which is journaled in suitable journals mounted on the trolley. The upper end of this shaft 34 is provided with a beveled gear 35 which is arranged to 50 be driven by a beveled gear driven by means of a motor 36 through suitable reducing gears.

The operation of the device is as follows: The charging apparatus is first lowered 55 by means of its motor to bring the charging arm into position over the slab to be charged into the furnace and the piece is gripped thereby in the usual manner, the charging apparatus is then raised and the crane 60 moved to a position in front of the furnace. The trolley is then moved in a lateral direction to move the arm 18 and the billet supported thereby into the furnace. The column, together with the entire charging apparatus, may then be rotated by means of

the gearing heretofore described in order to place the billet in the right position to be lowered on to the hearth of the furnace, the column being rotated by means of the pinion 33 and the gear member 23. The power 70 is applied to the column through the friction disks 25 and as soon as the power is cut off from the motor, the gear member 23 will come to rest and the friction disks will arrest the movement of the charging apparatus and the arm 18. It will, therefore, readily be understood that the momentum 75 of the arm 8 will be checked irrespective of the load, as the greater the load on the arm, the greater the friction of the disks. 80

In the specific apparatus shown and described, I have shown what is known to the art as the overhead charging apparatus for charging slabs into furnaces, but it will readily be understood by those familiar with 85 the art that the device is equally applicable to charging devices for open hearth furnaces and various other types of furnaces and also that it can be used in connection with floor chargers, locomotive cranes and 90 similar devices which are provided with a load supporting arm arranged to be rotated about an axis.

The advantages of my invention result 95 from the provision of frictional devices between a load to be rotated and the rotating mechanism therefor, which is so arranged that the load is supported by the friction members so that the friction will vary in accordance with the load. 100

I claim:

1. A device of the character described, comprising a rotary load carrying member, a rotary driving member therefor, friction driving members interposed between the 105 load carrying member and the driving member on which the load carrying member is supported, the arrangement being such that the load is supported by the driving member through interposition of the friction driving members to vary the friction in proportion to the load; substantially as described. 110

2. A charging crane, comprising a column rotatable about a vertical axis, charging apparatus supported thereby, a bearing for 115 supporting said column, a driving gear rotatable about a vertical axis for rotating the column supported on the column bearing, means on the driving gear for supporting said column, said means including friction 120 members connected to the gear and the column which support the weight of the column whereby the friction between the driving gear and the column is varied in proportion to the load carried by the charging apparatus; substantially as described. 125

3. A charging crane comprising a bridge, a trolley movable thereon, a bearing supported by the trolley, a gear wheel rotatably mounted on said bearing, a plurality of fric- 130

tion disks mounted on said gear wheel, a column for supporting a charging apparatus rotatably mounted in said bearing and supported on said friction disks, means for securing alternate friction disks to the column, and means for securing alternate friction disks to the gear wheel, the arrangement being such that the column is rotated by means of the gear wheel through the medium of the friction disks; substantially as described.

5 4. A charging crane comprising a bridge, a trolley movable thereon, a bearing supported by the trolley, a gear wheel rotatably mounted on said bearing, anti-friction rollers interposed between said bearing and gear wheel, a plurality of friction disks mounted on said gear wheel, a column for supporting a charging apparatus rotatably mounted in said bearing and supported on said friction disks, means for securing alternate friction disks to the column, and means for securing alternate friction disks to the gear wheel, the arrangement being such that

10 20 25 the column is rotated by means of the gear

wheel through the medium of the friction disks; substantially as described.

5. A support for a column for a charging apparatus, comprising a bearing, a gear wheel rotatably mounted on said bearing, 30 roller bearings between said gear wheel and the face of said bearing, a spindle on said column rotatably mounted within the bearing and surrounded by said gear wheel, a plurality of friction disks on said gear 35 wheel, and a flange member connected to the spindle of the column and supported on the upper friction disk, means for connecting some of the friction disks to the column spindle to rotate therewith, and means for 40 connecting the remainder of said friction disks to the gear wheel; substantially as described.

In testimony whereof, I have hereunto set my hand.

DAVID KENDALL.
